Francis Henry's Design for Nursing Bottle.

Patented Sept. 14, 1858.

No. 1049.

Des. 1049

Francis Kern, of Sandwich, Mass.
Letters Patent No. 1049 Dated Sept 14. 1858.

The schedule referred to in these Letters Patent, and making part of the same.

To all whom it may concern:

Be it known that I, Francis Kern, of Sandwich, in the County of Barnstable, and State of Massachusetts, have invented or produced a new and original design for a nursing Bottle, and I do hereby declare that the following is a full, clear and exact description of the same reference being had to the annexed drawings making a part of this specification, in which,

Fig: 1. is a longitudinal section of a bottle with my design thereon.

Fig: 2. is an external view of do, showing clearly the design.

The design consists in having the portion of the bottle on which the name is shown in raised letters "Mothers Blessing" made in the form of a scroll each end of which is formed of leaves and berries.

In fig: 1. it will be seen that the portion a, is slightly raised from the body of the bottle, said portion forming the label portion of the bottle, and having the words "Mothers Blessing" formed of raised letters. The portion a, extends across the whole width of the bottle and it is of scroll form,

and each end terminates with a branch formed of leaves b, closely set together and berries c. The leaf branches are curved in opposite directions the upper end extending over the label portion a, and the other below it, the whole forming an S-shaped scroll at about the center of the side of the bottle.

I claim as new and desire to secure by Letters Patent,

The S-shaped scroll formed of the label portion a, and leaf branches b, and berries c, arranged or disposed as herein shown and described to form a new and ornamental design for a Nursing bottle.
